2,155,675

OZONIZER

Melvin J. Napier, Akron, Ohio, assignor to Lowell
Air Conditioning Corporation, Philadelphia,
Pa.

Original application March 30, 1936, Serial No.
71,768. Divided and this application December
5, 1936, Serial No. 114,494

2 Claims. (Cl. 204—32)

The present application is a division of Serial
Number 71,768 filed on March 30, 1936.

This invention relates to an improved air con-
ditioning apparatus by means of which ozone may
be produced and fed into a room to mix with air
5 therein and serve to purify the same.

Another object of the invention is to permit
the variable source of ozone to be easily adjusted
by an adjusting device having an actuating mem-
ber disposed externally of the housing where it
10 is readily accessible.

Other and further objects of the invention will
become apparent from a reading of the follow-
ing specification taken in conjunction with the
15 drawing, in which:

Figure 1 is a view of a modified form of con-
stant source of ozone, and

Figure 2 is a sectional view taken along line
15—15 of Figure 1.

An ozonizer may be constructed as shown in
Figures 1 and 2. In this form of ozone generator
a frame rests upon a platform and supports a
cylinder 119. The shaft 120 has its projecting
25 end portions resting in bearings 121 at the upper
ends of standards forming end positions of a
supporting frame for the cylinder.

These standards are provided with legs 123
at their lower ends and a cross bar 124 integrally
unites the standards and maintains them in an
30 upright position. Therefore, a rigid frame is
provided and the cylinder will be well supported.
Instead of using a curtain or sleeve as an outer
electrode, there has been provided an arcuate
35 plate 125 supported upon legs 126 which are of
such height that the plate or saddle 125 fits
snugly about the cylinder between the heads or

caps 127 of the cylinder. The saddle is lined with
screening as shown at 128 and when the device
is in operation and high voltage current is pass-
ing through the glass cylinder ozone will be
formed.

While but one form of the invention has been
herein shown and described, it will be apparent
to those skilled in the art that various minor
modifications may be made without departing
from the spirit of the invention of a scope of the
10 appended claims.

What is claimed is:

1. In an air conditioner, an ozone generator
comprising a support having end standards, a
glass cylinder, heads of insulation closing ends 15
of said cylinder, a metal sleeve fitting snugly
within said cylinder between the heads and con-
stituting an inner electrode, a metal shaft ex-
tending axially through the cylinder with end
portions passing through the heads and sup-
ported by said standards, and adapted to have
a circuit wire attached thereto, an arm extending
20 radially from said shaft within the cylinder and
engaging the metal sleeve, and a metal trough-
shaped plate bearing against the under portion 25
of the cylinder between the caps and having de-
pending supporting legs, said plate constituting
an outer electrode and adapted to have a circuit
wire connected therewith.

2. The structure of claim 1 wherein the sleeves 30
are formed of woven wire fabric having its
strands extending spirally about the cylinder
whereby the sleeves may be diametrically adjust-
ed to fit the cylinder.
